(57) **CLAIM**

The ornamental design for a speed measuring device, as shown and described.

DESCRIPTION

FIG. 1 is a perspective view of front, top and left side of a speed measuring device showing our new design;

FIG. 2 is a front view thereof;

FIG. 3 is a rear view thereof;

FIG. 4 is a right side view thereof;

FIG. 5 is a top view thereof;

FIG. 6 is a bottom view thereof; and,

FIG. 7 is a front view showing usage thereof.

The portions of the article in broken lines are shown for illustrative purposes only and form no part of the claimed design.
